DESIGN FOR A MOLD FOR LAMB PATTIES OR THE LIKE

Harvey Geroux, Los Angeles, Calif.

Application August 13, 1935, Serial No. 58,097

Term of patent 7 years

To all whom it may concern:

Be it known that I, Harvey Geroux, a citizen of the United States, residing at Los Angeles, in the county of Los Angeles and State of California, have invented a new, original, and ornamental Design for a Mold for Lamb Patties or the like, of which the following is a specification, reference being had to the accompanying drawing, forming part thereof.

Fig. 1 is a perspective view of the mold, showing my design, the handle portions thereof being shown broken away.

Fig. 2 is a side elevational view.

Fig. 3 is a sectional view taken on line 3—3 of Fig. 2.

Fig. 4 is a rear end view.

I claim:

The ornamental design for a mold for lamb patties or the like, as shown and described.

In testimony whereof, I affix my signature.

HARVEY GEROUX.
